COMBINATION SMOKING PIPE, CIGARETTE
HOLDER, AND SALIVA TRAP

Joseph George Sciavolino, Hoboken, N. J.

Application August 6, 1938, Serial No. 223,397

1 Claim. (Cl. 131—211)

This invention relates to combination smoking pipes and cigarette holders. It is particularly directed to a pipe having a stem which may be used as a cigarette holder.

5 An object of this invention is to provide a pipe of the character described, so constructed as to keep the bottom of the bowl dry.

Another object of this invention is to provide a pipe of the character described, which shall be 10 relatively inexpensive to manufacture, easy to assemble, disassemble and clean, and which shall yet be practical and efficient to a high degree in use.

Other objects of this invention will in part be 15 obvious and in part hereinafter pointed out.

The invention accordingly consists in the features of construction, combinations of elements, and arrangement of parts which will be exemplified in the construction hereinafter described, 20 and of which the scope of application will be indicated in the following claim.

In the accompanying drawing, in which is shown one of the various possible illustrative embodiments of this invention,

25 Figure 1 is an axial, elevational, cross-sectional view of a combination pipe and cigarette holder embodying the invention;

Figure 2 is an axial, cross-sectional view of the stem of the pipe used as a cigarette holder; and

30 Figure 3 is an axial, elevational, cross-sectional view, similar to Figure 1, but illustrating a modified construction.

Referring now in detail to the drawing, 10 35 designates a combination pipe and cigarette holder embodying the invention. The same comprises a member 11 having a bowl portion 12 and a shank portion 13, extending at right angles to the bowl. The shank portion 13 has a reduced cylindrical portion 14 formed with a 40 conical end surface 15. The shank 13 has an axial through bore 16 extending from the bottom of the bowl to the apex of the conical portion or surface 15.

45 Frictionally attached to the shank 13 is a stem 17, which may be used as a cigarette holder, as will be explained hereinafter. The stem 17 tapers toward the tip 18, which is received within the mouth of the smoker, and has a socket 19 at the larger end, adapted to frictionally receive the cylindrical portion 14 of the shank. The outer end 20 of the stem 17 abuts the shoulder 21 of the shank at the reduced portion 14. The socket 19 is longer than the cylindrical portion 14, and the bottom of the socket is formed with

a conical surface 23. The stem has a narrow through opening 24, communicating with the socket 19.

Extending within the through bore 16 of the shank 13, is a metal pipe 27 having a conical 5 portion 28 at one end receiving and contacting the conical portion 15 of the shank.

It will now be understood that saliva will be trapped in the space between the portion 28 of member 16 and the bottom 23 of the socket 19. 10 The saliva so trapped may be readily cleaned out.

The stem 17 may be removed from the shank, and a cigarette 30 may be inserted within the socket 19. Any suitable absorbent material 31 15 may be placed into the bottom of the socket 19 to absorb nicotine or saliva.

In Figure 3 there is shown a pipe 10a illustrating a modified form of the invention. In Figure 3 there is disclosed a member 40 comprising 20 a bowl portion 41 and a shank portion 42. The shank portion 42 is formed with a socket 43 and with a through opening 44, communicating with the bottom of the bowl and with the socket 43.

Attached to the member 40 is a metal member 45 comprising a central collar portion 46, engaging the outer end of the shank 42, a tubular portion 47 disposed within the socket 43, and a reduced portion 48 disposed within the through opening 44.

Extending from the collar 46 is an axial, externally screw threaded portion 49, from which there extends a conical portion 50. The member 45 is provided with an axial through opening, 30 as shown in the drawing.

Screwed to the screw threaded portion 49 is a stem 52 formed with a socket 55 to provide a chamber between the portion 50 of member 45 and the bottom of said socket. The bottom 56 of the socket 55 may be conical, as shown in 40 Figure 3.

It will now be understood that the pipe 10a may be easily disassembled and assembled, and that saliva and nicotine may be trapped in the chamber 55.

45 It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accom- 50 55

panying drawing is to be interpreted as illustrative and not in a limiting sense.

Having thus described my invention I claim as new, and desire to secure by Letters Patent:

- 5   A smoking pipe comprising a member having a bowl portion, and a shank extending therefrom, said shank being formed with a reduced cylindrical portion, the outer end of said cylindrical portion being conical, and said shank be-
10   ing formed with a through opening extending from the bottom of the bowl to the apex of said

conical portion, a member made of metal having a pipe portion extending within said through opening and having a conical portion at one end of said pipe portion receiving the conical portion of the shank, and a stem having a socket at one end receiving the cylindrical portion of the shank, said socket being of such length as to provide a chamber between the conical portion of said metal member and the bottom of said socket. 5
10

JOSEPH GEORGE SCIAVOLINO.
